WIRE TYING MACHINE

Parvin Wright, Los Angeles, Calif.

Application April 4, 1933, Serial No. 664,443

34 Claims. (Cl. 140—93)

This invention relates to machines for tying packages and boxes with wire, having for its object to provide a device simple in construction and more efficient in operation than those here-
5 tofore proposed.

With these and other objects in view the invention resides in the novel details of construction and combinations of parts as will be disclosed more fully hereinafter and particularly
10 pointed out in the claims.

Referring to the drawings forming a part of this specification and in which like numerals designate like parts in all the views,

Fig. 1 is a front elevational view of the machine with the gear casing cover removed, the parts being shown ready for manipulation to tension the wire and twist the knot therein;

Fig. 2 is a top plan view of the parts shown in Fig. 1;

Fig. 3 is a view similar to Fig. 1 but showing the parts at the end of the tensioning and twisting operation;

Fig. 4 is a separated perspective view showing details of construction and arrangement of the
25 wire holding dog and latch therefor;

Fig. 5 is a vertical cross sectional view taken to the rear of the holding dog;

Fig. 6 is a detail sectional view illustrating the securement of the box contacting plate with
30 the base plate of the machine;

Fig. 7 is a detail view illustrating the operation of the cutter on the right hand side of the machine as seen in Fig. 3, said view looking in a direction away from the twister pinion;

Fig. 8 is an elevational view of the left side of
35 the machine as shown in Fig. 1;

Fig. 9 is an elevational view of the right side of the machine as shown in Fig. 1;

Fig. 10 is a perspective view of the twister
40 pinion;

Fig. 11 is a perspective view of the housing or mounting for the twister pinion;

Fig. 12 is a view illustrating the securement of the twister pinion housing to the base plate
45 of the machine; and

Fig. 13 is a view of the knot formed by this machine.

This invention comprises generally a casing indicated at 1 which is hollow to provide space for a
50 spur gear 2 rigidly secured to a shaft 3 extending transversely of the casing and journaled in the side walls 4 and 5 thereof. The shaft extends through the wall 4 and carries at its end a bevel pinion 6 meshing with an arcuate segment rack
55 7 carried by the handle 8 pivoted as at 9 to an

ear 10 extending laterally from the wall 4 of the casing. The shaft 3 also extends through the other wall 5 with its ends engaged by a nut or other suitable means for securing the shaft in position relative the casing, insuring the functioning of the gears 2 and 6.

With particular reference to Figs. 1, 10, 11 and 12 it will be seen that the gear 2 meshes with the twister pinion 15 of the usual and well known type in that it is provided with laterally extending trunnions 16 and 17 and is provided with the radial slot 18 to permit the two bights of wire forming the tie for the package to be placed at substantially the center of the twister pinion. Said pinion is mounted in a housing formed by two blocks 19 and 20, the former being provided with a recess 21 cut in from two adjacent sides, said recess to accommodate the toothed portion of the twister pinion. Both blocks 19 and 20 are formed with bearings 22 and 23 for the trunnions 17 and 16 respectively, both blocks at one end being formed with the mouth portions 24 and 25 leading to the slotted portions of the trunnions of the twister pinion and the slot 18 thereof. It will, of course, be understood that the mouth portions 24 and 25 are oppositely curved, or flared upwardly and downwardly as shown in Fig. 12, to provide easy ingress for the wires of the tie into the twister pinion.

As usual in constructions of this character the slot 18 of the pinion will be of a dimension only slightly greater than the diameter of a bight of the wire tie. On the other hand, the trunnions 16 and 17 as well as the mouth portions 24 and 25 of the pinion housing blocks, each have a dimension slightly greater than twice the diameter of the wire tie, so that when the knot shown in Fig. 13 is formed, the twist portions thereof will not bind but may slip readily from the trunnions through the mouth portions of the twister pinion 95 housing.

The blocks 19 and 20 may be secured together in any suitable manner such as by a bolt passing through the opening 26 of block 20 and threaded into the other block 19, registration of the trunnion bearings 22 and 23 being insured by employment of the dowel pins 27 and 28, or the like. One or both of the blocks is secured by one or more screws such as 29 to the base plate 30 of the machine, as clearly shown in Fig. 12, and 105 preferably the assembled blocks are set close in a cut-out portion of the bottom wall 96 of the casing to additionally insure retention of the pinion in operating position.

The opposite walls 4 and 5 of the casing 1 are 110

each provided with a suitable slotway disposed in registration with the mouth portions 24 and 25 and the slot of the twister pinion to permit ready entry of the bights of the tie wire as will be readily understood. The side wall 4 has secured to the outer surface thereof a steel plate 35 provided with a mouth portion 36 similar to the portion 24 of the block 19, and against the outer side of the plate 35 is secured an L-shaped casting generally indicated by the numeral 37, the horizontal portion of which constitutes an anvil 38 against the upper surface of which the free end of the wire tie may be secured as by the holding dog 39. A suitable bolt 40 secures the parts 35 and 37 to 15 the side wall 4 of the casing.

The dog 39 is rigidly secured to the forward end of an oscillatory shaft 41 which extends through the upper portion of the casting 37 and carries at its rear end a lug generally indicated by the 20 numeral 42. Through the depending portion of this lug extends a bolt 43 passing through the wall 4 of the casing and provided at its inner end with the nut 44 and an interposed spring 45 which latter exerts a pressure tending to draw 25 the lug 42 toward the plate 35. This normally causes the bottom serrated surface 46 of the dog 39 to positively engage and grip the end of the wire tie against the anvil 38.

The dog 39 is provided with a tooth or projection 47 adapted to engage the latch or trip plate 48 when the dog is oscillated after the knot has been tied, thereby freeing the dog from its wire gripping position. This trip plate is mounted adjacent the anvil casting 38, being supported 30 on pins such as 49 extending through the holes 50 and 51 of the latch plate, to and through corresponding holes in the anvil casting through corresponding holes in the steel plate 35, and having their ends threaded as shown in Fig. 5 35 into the side wall 4 of the casing. Light coil springs 52 are disposed between the heads of the pins 49 and the outer surface of the trip plate 48 to normally urge the latter against the vertical side wall of the anvil casting, said trip plate 40 being yieldable against the tension of these 45 springs during oscillation of the dog.

A rod 55 extends forwardly from the bottom portion of the lever handle 8 and is adapted, upon downward movement of said handle, to contact the under side of the extension 56 of the dog 39, see Fig. 3, and to oscillate said dog sufficiently in a clockwise direction as seen in said figure to release it from the tie wire and to cause the tooth 47 thereof to snap into position on the 50 upper surface of the yieldable latch. At this time the handle 8 will be in its lowermost position and when the handle is again moved upwardly the latch plate will hold the dog in the position shown in Fig. 3 so that the twisted knot may be 55 freely expelled from the machine. In other words, the parts are shown in Fig. 3 at the end of the down stroke of handle 8 which, through the gears 7, 6 and 2, has caused the necessary revolutions of the twister pinion 15 to form the knot, the releasing and latching of the dog 39 taking place at the completion of the formation 60 of the knot.

The other side of the machine is particularly illustrated in Fig. 9 but with further reference to 70 Figs. 1, 2 and 3, it will be seen that there is provided another ear 60, similar to ear 10 in that it expands laterally from the casing 1, and to this ear is pivoted as at 61 the lever handle 62 carrying a stud roller 63 adapted to ride in the arcuate 75 slot 64 of a lever 65 pivoted at its upper end as at

66 to a boss 67 formed on the casing 1. The parts 60, 62, 65 and 67 are disposed in parallel planes which are inclined to the vertical plane passing through the ear 10, the purpose of this inclination being to permit operation of the tensioning and cutting mechanisms in more practical and efficient manners.

Figs. 1 and 3 clearly show the operation of the tensioning members of this machine. In other words, the lever 65 is operable to swing its lower end outwardly by virtue of the movement of the roller 63 in slot 64. On the front face of the lever 65 there is formed a lug 68 at the bottom thereof and coacting with the upper surface of this lug is a second spring pressed dog 69 pivoted as at 70 so that the loose free end of the wire tie may be gripped between said dog and said lug, the lower portion of the dog having an extending pin 71 over which the end of the wire may be looped, as will be readily understood from the drawings. By inclining the lever and other parts as hereinbefore mentioned, this dog 69 and the anvil lug 68 will create a pull on the held wire more nearly in line with the bight which passes through the twister pinion, thereby creating a lesser bend of the tie wire in passing from the side wall 5 of the casing to said dog.

The vertical wall 5 of the casing is formed with a mouth portion similar to those hereinbefore described to provide means of inserting and withdrawing the bights of the tie wire from positions in which the knot is formed, and to the outer surface of the wall 5 there is secured a steel plate 85 similar to the companion plate 35 on the opposite side of the machine and against the outer surface of the plate 85 there is pivoted as at 75 a cutter generally indicated by the numeral 76 clearly shown in Fig. 7, with cutter edge 77, and notch 78 to straddle the bight of the wire tie not desired to be cut. The extreme lower edge of the cutter is made flat to engage the surface of a leaf-spring 79 secured at one end as at 80 to the base plate 30 of the machine, the disposition of parts being such that when no tension is placed on the cutter member 76 to oscillate it about its pivot 75, the cutting edge 77 will lie immediately above the free end of the wire tie which is subsequently to be severed. The upper end of the cutter member 76 carries a roller 81 so positioned as to lie in the plane of the lever handle 62 so that a cam 82 carried by said handle will strike said roller and oscillate the cutter member, see Figs. 3 and 7.

This cam 82 is mounted on the handle at a point near the lower end thereof when the handle is in raised position, so that when the handle is moved downwardly, to tension the wire, the cam 82 will be moved upwardly and during this movement the cam will, due to its inclination, cause the roller 81 to move the cutter member 76 about its pivot to raise the cutting edge 77 still further above the tie wire, this movement being an inoperative oscillation of the cutter. On the other hand, when the handle 62 is raised, the cam 82 will move downwardly, and in this directional movement the opposite face of the cam will cause the roller 81 to move the cutter member oppositely about its pivot so that the cutting edge will move downwardly, with a relatively quick movement, to sever the bight of the tie wire which passes to the tensioning dog 69, but will not cut the other bight which encompasses the box because of the notch 78.

In operation, the tie wire is inserted in the well known manner through the several mouth

80

- portions hereinbefore mentioned and the extreme end of this wire is pushed axially against the trip plate 48, thereby moving said plate against the tension of the light springs 52 and releasing the tooth 47 of the dog 39 to permit oscillation of said dog to bring its serrated surface into gripping position on the end of the wire, forcing said wire against the surface of the anvil 38. It is to be observed that this anvil surface is inclined downwardly in an outward direction, so that the pressure of the dog 39 will cause a slight downward bend of the held end of the wire. This provides a "set" of said end which, after the knot is twisted and released, causes the end to be depressed below the upper surface of the knot so that said end cannot tear or injure superposed packages nor the hands of those moving the tied package. With the end of the wire thus secured by the dog 39, the bight 86 lying in the innermost extremity 20 of the twister pinion slot is passed to the edge of the box, thence downwardly and under the box, thence upwardly on the other side, and thence over the top of the box as bight 87, see Figs. 1 to 4, and inserted in said various mouth 25 portions and twister pinion, with the extreme free end of the wire, indicated at 88, passed between the tensioning dog 69 and the lug 68 and thence looped around the post 71 of said dog. It will, of course, be understood that during 30 the placement of the wire tie around the box, both handles 8 and 62 will be in raised position, as seen in Fig. 1.
- The handle 62 is then moved downwardly about its pivot 61, which causes an outward swing of 35 the tensioning lever 65, causing the dog 69 to grip more tightly the free end 88 of the wire, and to transmit the increasing tension axially throughout the wire tie about the box, as is well understood. When the handle 62 has reached 40 the lowermost extremity of its stroke as indicated in Fig. 3, the wire will have been greatly tensioned, both bights forced to the inner extremities of the slots provided therefor in the side walls and the twister pinion, and the knot 45 is then ready to be formed.
- The handle 8 is then depressed or moved downwardly which actuates the twister pinion through the intermediate gears 6 and 2, and since the slots of the mouth portions of the side 50 plates 35 and 85, as well as the slot 18 of the twister pinion are of a dimension only slightly greater than the diameter of each bight of the tie wire, the two bights will be maintained in parallel untwisted relationship at said plates and at 55 the middle portion of the twister pinion. The two bights between these portions, however, will be twisted together with the ultimate formation of the knot shown in Fig. 13.
- With particular reference to Figs. 1 and 3, it 60 will be seen that there is provided a screw 90, workable into and out of a portion of the casing 1, for limiting the upward throw of the handle 8. In other words, this screw is moved into or out of the casting of the casing and ultimately secured in that position which, when the handle 8 is thereagainst, will insure a registration of the slot of the twister pinion with the slots of the side plates 35 and 85. A similar screw 97, co-operable with the lug 98 formed on said handle, 65 is provided for insuring similar registration at the lowermost throw of said handle, thereby permitting discharge of the twisted knot. Hence, at the end of the tensioning and twisting operations, both handles will be down, and when the tensioning handle is raised, the free end of the 70 wire 88 will be severed from the knot. With the twisting handle 8 still down, the operator then tips the entire machine forward by means of the elevated tensioning handle, thereby releasing the knotted tie from the machine because of the registration of slotways. 80
- As hereinbefore stated, this machine is provided with a base plate 30 extending under all portions thereof. However, it has been found in heretofore known constructions that tying machines would stick or be otherwise obstructed from moving readily over the upper surface of the box or package and hence an important feature of this invention lies in the provision of means to permit movement of the machine in a direction axial of the tie wire during the tensioning and twisting operation, whereby the tension created by the machine on the tie wire may be distributed more equally in both bights 86 and 87 of the tie. 85
- To this end the device is provided with a package or box contact plate 91 wholly underlying the base plate 30, said contact plate provided at intervals with teeth or other projections, or otherwise suitable roughened, to cause a gripping between said plate and the surface of the box. The extreme rear edge of the contact plate 91 is turned upwardly and over the base plate 30 as indicated at 92 in Fig. 8, and the opposite or forward edge of the contact plate is provided at suitable intervals with horizontally elongated slots 93 to receive therethrough headed bolts 94 threaded into the correspondingly upwardly rolled forward edge portion of the base plate 30. 90
- Suitable anti-friction rollers 95 are disposed between the machine proper and the upper surface of the contact plate 91, said rollers being shown in Figs. 1 and 5 and retained in position as by counter sinking in the bottom wall 96 of the casting forming the casing 1, these rollers being provided at suitable spaced intervals. For convenience the casing 1 may be made in two or more parts, there being shown in Figs. 8 and 9 a construction providing a front cover portion 99 secured as by the bolts 100 to the main body portion of the casing to permit ready access to the various moving parts. Preferably the joint between this cover portion 99 and the main portion of the casting is formed in an axial plane of the gear shaft 3 so that each of said portions will constitute a half-bearing for said shaft. 100
- Suitable anti-friction rollers 95 are disposed between the machine proper and the upper surface of the contact plate 91, said rollers being shown in Figs. 1 and 5 and retained in position as by counter sinking in the bottom wall 96 of the casting forming the casing 1, these rollers being provided at suitable spaced intervals. For convenience the casing 1 may be made in two or more parts, there being shown in Figs. 8 and 9 a construction providing a front cover portion 99 secured as by the bolts 100 to the main body portion of the casing to permit ready access to the various moving parts. Preferably the joint between this cover portion 99 and the main portion of the casting is formed in an axial plane of the gear shaft 3 so that each of said portions will constitute a half-bearing for said shaft. 105
- From the foregoing disclosure it will therefore be seen that by this invention there is provided a machine for tying the ends of a wire passed for example around a box, the tie being in the nature of a twisted knot. The device is provided with means for tensioning one bight of the wire, as well as a pinion adapted to twist the parallel bights of the wire in the machine to form the knot, there being provided the levers 62 and 8 respectively for actuating the tensioning and the twisting, said levers being mounted substantially for operation in planes parallel to the axis of the wire tie. Also these levers are operable in opposite directions on opposite sides of the machine. 110
- In addition the tensioning lever 62 is operable in one direction to tension the wire and when operated in the opposite direction it actuates the cutter 76 to sever the end of the twisted wire. During the tensioning operation, the machine is permitted a rolling movement over the undermost plate 91 which is provided on its under surface with box engaging means in the nature of 115
- 120
- 125
- 130
- 135
- 140
- 145
- 150

projections or the like. Lastly the tensioning lever 62 is utilized in its raised position and after the knot is tied, to tip or roll the entire frame of the machine forward over the upwardly curved bottom edge of the device to permit the ejection of the twisted knot from the machine.

The clamping means for the tie wire comprises the dog 39 which is pivoted and provided with a tooth 47 as well as a laterally extending arm 56 so that when the pin 55 carried by the lever 8 for actuating the twister pinion, is moved arcuately, said pin will strike said arm and oscillate the dog to release the same from the end of the tie wire, and in this movement the tooth 47 will snap over the upper edge of the yieldable plate 48 and hold the dog in released position until it is tripped by the next inserted wire.

It is obvious that those skilled in the art may vary the details of construction as well as arrangements of parts without departing from the spirit of the invention, and therefore it is not desired to be limited to the foregoing except as may be required by the claims.

What is claimed is:—

25. 1. In a wire tying machine the combination of means operable in one direction to tension the wire; independently operated wire twisting means; and a cutter operable by the reverse movement of the tensioning means for severing the end of the twisted wire.

2. In a wire tying machine the combination of means operable in one direction to tension the wire; a cam carried by said means; independently operated wire twisting means; and a cutter actuated by said cam and operable by the reverse movement of the tensioning means for severing the end of the twisted wire.

3. In a wire tying machine the combination of pivoted means operable in one direction to tension the wire; a cam carried by said means; wire twisting means; and a pivoted cutter actuated by said cam during the reverse movement of the tensioning means to sever the end of the twisted wire, said cam inoperatively oscillating said cutter during the tensioning operation.

4. In a wire tying machine the combination of a frame provided with a pair of spaced similar slots to receive therein parallel bights of a wire; wire twisting means provided with a slot registerable with the slots of said frame at the beginning and at the end of the twisting operation; pivoted means independently operated of the twisting means for tensioning the wire when operated in one direction; and a cutter for severing one of said bights, the cutting operation effected by reverse movement of the tensioning means.

5. In a box wiring machine the combination of a frame provided with means for receiving, tensioning and twisting the ends of the applied wire; and a plate carried by said frame and over which said frame may move during the tensioning and twisting operations, said plate provided with box engaging means.

6. In a box wiring machine the combination of a frame provided with means for receiving, tensioning and twisting the ends of the applied wire; and a plate carried by said frame and over which said frame may move during the tensioning and twisting operations, said plate having its under surface provided with box engaging means.

7. In a box wiring machine the combination of a frame provided with means for receiving, tensioning and twisting the ends of the applied wire; and a plate interposed between the box and said frame, said plate carried by said frame and over

which said frame may move during the tensioning and twisting operations, said plate provided with box engaging means.

8. In a box wiring machine the combination of a frame provided with means for receiving, tensioning and twisting the ends of the applied wire; and a plate slidably secured to the bottom of said frame and separating said frame from the box, said plate provided with box engaging means whereby said frame is permitted movement relative the box during the tensioning and twisting operations. 80

9. In a box wiring machine the combination of a frame provided with means for receiving, tensioning and twisting the ends of the applied wire; a plate slidably secured to the bottom of said frame and separating said frame from the box, said plate provided with box engaging means; and rollers interposed between said plate and said frame whereby the latter is permitted movement relative the box during the tensioning and twisting operations. 85

10. In a wire tying machine the combination of a frame provided with wire receiving slots and associated wire tensioning and wire twisting means; means for clamping the end of a wire adjacent one of said slots; means to release said clamping means at the end of the twisting operation; and means to hold said clamping means in released position until tripped by the next inserted wire. 100

11. In a wire tying machine the combination of a frame provided with wire receiving slots and associated wire tensioning and wire twisting means; means for clamping the end of a wire adjacent one of said slots, said means provided with a tooth; means to release said clamping means at the end of the twisting operation; and means engageable with said tooth to hold said clamping means in released position until tripped by the next inserted wire. 110

12. In a wire tying machine the combination of a frame provided with wire receiving slots and associated wire tensioning and wire twisting means; means for clamping the end of a wire adjacent one of said slots, said means provided with a lateral extension; means engageable with said extension to release said clamping means at the end of the twisting operation; and means to hold said clamping means in released position until tripped by the next inserted wire. 120

13. In a wire tying machine the combination of a frame provided with wire receiving slots and associated wire tensioning and wire twisting means; means for clamping the end of a wire adjacent one of said slots, said means provided with a tooth as well as with a lateral extension; means engageable with said extension to release said clamping means at the end of the twisting operation; and means engageable with said tooth to hold said clamping means in released position until tripped by the next inserted wire. 130

14. In a wire tying machine the combination of a frame provided with wire receiving slots and associated wire tensioning and wire twisting means, the wire twisting means including an operating lever; a pivoted dog for clamping the end of a wire adjacent one of said slots, said dog provided with a laterally extending tooth as well as with an extending arm; means comprising an extension from said lever engageable with said arm to release said dog at the end of the twisting operation; and means comprising a yield- 140

150

able plate to hold said dog in released position until tripped by the next inserted wire.

15. In a wire tying machine the combination of a frame for receiving two bights of a wire; means for twisting said bights together to form a knot; and means for tensioning one of said bights prior to the twisting operation, said means including a compound leverage comprising two members each pivoted to said frame, one member provided with a cam slot receiving therein an extension of the other member.

16. In a wire tying machine the combination of a frame for receiving two bights of a wire; means to tension one of said bights; means to twist said bights together after tensioning; and a pair of operating handles, one for actuating the tensioning means and the other for actuating the twisting means, and handles operatively movable in directions away from the twisting means.

20. In a wire tying machine the combination of a frame for receiving two bights of a wire; means to tension one of said bights; means to twist said bights together after tensioning; and a pair of operating handles disposed on opposite sides of the twisting means and operatively movable in directions away therefrom, one handle for actuating the tensioning means and the other for actuating the twisting means.

25. In a wire tying machine the combination of a frame for receiving two bights of a wire; a pinion for twisting said bights together; a mounting for said pinion comprising two journal blocks each receiving therein one of the trunnions of said pinion, one of said blocks provided with a recess for receiving said pinion, both of said blocks secured together as well as to a wall of said frame; and means to actuate said pinion.

30. In a wire tying machine the combination of a frame for receiving two bights of a wire, said frame having its bottom forward edge upwardly curved to provide a rolling surface; means for twisting said bights together to form a knot; and means for tensioning one of said bights prior to the twisting operation, said means including a compound leverage one member of which is provided with a cam slot receiving therein an extension of the other member, said other member constituting means for rolling said frame forwardly about its curved edge to cause the ejection of the twisted knot.

35. In a wire tying machine the combination of a frame for receiving two bights of a wire, said frame having its bottom forward edge upwardly curved to provide a rolling surface; means for twisting said bights together to form a knot; and means for tensioning one of said bights prior to the twisting operation, said means including a lever constituting a handle for rolling said frame forwardly about its curved edge to cause the ejection of the twisted knot.

40. In a wire tying machine the combination of a lever to tension the wire; a cam formed as a plate extension of the edge of said lever; independently operated wire twisting means; a pivoted cutter under spring tension; and an extension from said cutter disposed in the path of said cam for actuation by the latter.

45. In a wire tying machine the combination of a lever to tension the wire; a cam formed as a plate extension of the edge of said lever; independently operated wire twisting means; a pivoted cutter under spring tension; and an extension from said cutter disposed in the path of said cam for actuation by the latter, said cam inop-

eratively oscillating said cutter when said lever is tensioning the wire but causing a cutting oscillation upon the reverse movement of said lever.

50. In a wire tying machine the combination of a lever to tension the wire; a plate extension of the edge of said lever, said extension constituting a cam having opposite engageable surfaces; wire twisting means; a pivoted cutter under spring tension; and an extension from said cutter disposed in the path of said cam for actuation by the latter, one surface of said cam inoperatively engaging the cutter extension during the tensioning movement of said lever, and the other surface of said cam causing a cutting oscillation of the cutter upon the reverse movement of said lever.

55. In a wire tying machine the combination of a lever to tension the wire; a plate extension of the edge of said lever, said extension constituting a cam having opposite engageable surfaces; wire twisting means; a pivoted cutter under spring tension; and an extension from said cutter disposed in the plane of said lever for actuation by said cam, one surface of said cam inoperatively engaging the cutter extension during the tensioning movement of said lever, and the other surface of said cam causing a cutting oscillation of the cutter upon the reverse movement of said lever.

60. In a wire tying machine the combination of wire tensioning and wire twisting means; a lever for actuating the tensioning means; a cutter for severing the wire after the twisting thereof, said cutter having an extension disposed in the plane of said lever; and a cam formed on the edge of said lever and adapted to pass the cutter extension when said lever is actuated in either direction, said cam having plural surfaces engageable with said extension, one surface engageable during the tensioning movement of said lever to cause inoperative actuation of the cutter, and the other surface engageable during the reverse movement of said lever to cause wire severing actuation of the cutter.

65. In a wire tying machine the combination of wire tensioning and wire twisting means; a lever for actuating the tensioning means; a cutter for severing the wire after the twisting thereof, said cutter disposed in a plane transverse to the plane of lever actuation but having an extension normally disposed in said plane of lever actuation; and a cam formed on the edge of said lever and adapted to completely pass the cutter extension when said lever is actuated in either direction, said cam having opposite surfaces engageable with said extension, one surface engageable during the tensioning movement of said lever to cause inoperative actuation of the cutter, and the other surface engageable during the reverse movement of said lever to cause wire severing actuation of the cutter.

70. In a box wiring machine the combination of a frame having mounted thereon means for receiving, tensioning and twisting the ends of the applied wire; and a plate carried by said frame and over which said frame and its associated means may move during the tensioning and twisting operations, said plate provided with box engaging means.

75. In a wire tying machine the combination of a frame for receiving two bights of a wire; means for twisting said bights together to form a knot; and means for tensioning one of said bights prior to the twisting operation, said means including two cooperating members each pivoted

- to said frame, one of said members engaging said bight.
29. In a wire tying machine the combination of a frame for receiving two bights of a wire; a pinion for twisting said bights together; a mounting for said pinion comprising two journal blocks each receiving therein one of the trunnions of said pinion, one of said blocks provided with a recess for receiving said pinion, both of said blocks secured together as well as to a wall of said frame; a slotway in each block for passing said bights to said pinion; and means to actuate said pinion.
30. In a wire tying machine the combination of a frame for receiving two bights of a wire; a pinion provided with a slotway for receiving and twisting said bights together; a mounting for said pinion comprising two journal blocks each provided with a bore for receiving therein one of the trunnions of said pinion, one of said blocks provided with a recess for receiving said pinion, each of said blocks provided with a slot radially disposed to its bore for passing said bights to the slotway of said pinion, both of said blocks secured together as well as to a wall of said frame; and means to actuate said pinion.
31. In a wire tying machine the combination of means operable in one direction to tension the wire; wire twisting means; a cutter for severing the end of the twisted wire; and a double acting cam mounted on the tensioning means, said cam
- inoperatively oscillating said cutter upon the tensioning movement of said first named means and operatively oscillating said cutter to sever the end of the twisted wire upon the reverse movement of the tensioning means.
32. In a wire tying machine having means to tension and then to twist the wire, the combination of a cutter to sever the end of the twisted wire; and means carried by the tensioning means for actuating said cutter in opposite directions, one only of which is operative to sever the wire.
33. In a wire tying machine the combination of an oscillatable member which when moved in one direction tensions the wire; wire twisting mechanism; a cutter for severing the end of the twisted wire; and means carried by said member for actuating said cutter, said means in one movement of said member actuating the cutter to sever the end of the twisted wire, and in the reverse movement of said member actuating the cutter inoperatively.
34. In a wire tying machine provided with twisting mechanism the combination of an oscillatable member for tensioning the wire previous to the twisting thereof; a cutter for severing the end of the twisted wire; and means carried by said member and actuating said cutter in each movement of said member, the actuation of said cutter to sever the end of the twisted wire taking place during one movement only of said member.
